UNITED STATES PATENT OFFICE.

GEORGE W. SCOTT, OF TROY, OHIO.

STORM-FRONT FOR VEHICLES.

1,095,933.

Specification of Letters Patent.

Patented May 5, 1914.

Application filed April 13, 1910. Serial No. 555,230.

To all whom it may concern:

Be it known that I, GEORGE W. SCOTT, a citizen of the United States, residing at Troy, in the county of Miami and State 5 of Ohio, have invented certain new and useful Improvements in Storm-Fronts for Vehicles, of which the following is a specification.

This invention relates to improvements 10 in storm fronts for vehicles.

An object of the invention is to provide a front which may be swung back beneath the top of the vehicle when not in use and which may also be entirely removed from 15 the vehicle top when desired.

A further object of the invention is to simplify and make more effective the devices of this character.

The invention consists in the constructions 20 and combinations of parts hereinafter shown and set forth in the claims.

In the accompanying drawings:—Figure 1 is a side elevation of a portion of the bed of a vehicle and its top showing my 25 improved storm front applied thereto. Fig. 2 is a rear elevation of the storm front and a portion of the front bow of the vehicle top. Fig. 3 is a detail view of a portion of the movable frame of the front showing 30 one of the springs connected therewith. Fig. 4 is a section on the line $\alpha-\alpha$ of Fig. 2. Fig. 5 is a perspective view in detail of a portion of the upper or stationary frame of the front showing one of its supporting arms connected therewith. Fig. 6 35 is an end view of the same. Fig. 7 is a perspective view in detail of one of the supporting arms for the upper frame.

Like parts are represented by similar 40 characters of reference in the several views.

In the said drawings, a represents the body of the vehicle, a' the top and a'' the front bow thereof.

The storm front proper has an upper 45 stationary frame b and a lower movable frame b'' . The upper stationary frame is preferably constructed of wood and is shaped to conform to the upper portion of the bow of the vehicle top and fits within 50 the same. The lower movable frame is preferably constructed of wire, covered by the usual water proof material which is provided with a transparent window, b'' .

The upper frame b , is removably secured to the front bow in the following manner: 55 Connected at each end of the frame b are a pair of plates b' which are bent in under the lower edge of the frame b so as to form loops or guides b^{12} to receive the arms b^3 ; these arms being formed square in cross section and being slightly less in cross sectional dimensions than the said loops so as to permit said arms to turn slightly in the loops for the purpose hereinafter described. The outer end of each of these arms is bent 65 downwardly as indicated at b^4 and provided with an offset portion b^5 of substantially the shape of the front bow, and are thence bent upwardly as indicated at b^6 , and preferably provided with a hook b^7 , at its upper end. 70 In assembling this frame in position within the bow the hooks b^7 are placed over the usual top prop joint b^8 of the vehicle top, by first turning the frame at right angles to the bow, with the frame on the inside of the bow 75 and the arms extending across the front edges of the bow. After the hooks have been engaged with the joints b^8 the frame can be swung forwardly to proper position within the bow which will cause the offset 80 portions b^5 thereof to straddle the bow, and they may be secured in position by securing the straps b^9 over the buttons b^{10} which project from the top of the bow and through the top proper. When the frame is in position the upwardly extending portions b^6 of the arms will project back of the joints, b^8 . 85 The hooks b^7 are simply for the purpose of facilitating the assembling of the frame, b , within the bow and serve no purpose of 90 holding the same in position; in fact, said hooks may project above the joints after the parts are assembled, as shown in Fig. 1. The positions of the joints b^8 vary with respect to the top of the front bow in different 95 vehicles, and the portions b^4 , and b^6 of the supporting arms are made of such lengths as to compensate for the different positions of the joints, it only being necessary that the portions b^6 of the arms shall extend up 100 back of the said joints when the parts are assembled. The arms b^3 are slidable within the guides b^{12} so as to accommodate them to different widths of tops and when the stationary frame is in position the tension will 105 be such as to cause said arms to turn in the

guides and become bound therein to prevent movement of the frame, as shown in Fig. 6.

The lower movable frame b^2 is hingedly connected with the upper frame, b , and is provided with springs for normally holding the same in position under the top as indicated in dotted lines in Fig. 1. The upper frame b has connected to each side a plate or clip, c , each of which is provided with a rounded offset portion c' . These plates extend below the lower edge of the frame b , and are bent at their lower ends so as to form sleeves c^2 in which sleeves are located a hollow rod c^4 which extends from one plate to the other. The top wire of the frame b^2 is journaled in this hollow rod so that the lower frame will be free to swing with respect to the upper frame. Located in each of the offset portions c' is a coiled spring c^5 , one end c^6 of which extends down parallel with the side frame or wire of the frame b^2 and is hooked about the same; the other free end of said spring being hooked about the rod c^4 . The normal tendency of these springs is to throw the frame b^2 up under the top as previously explained. The wires of the frame b^2 are bent at each lower corner so as to form hooks c^{11} , which hooks are adapted to be engaged by eyes c^8 upon straps c^9 secured to the apron c^{10} which fits over the dashboard in the usual way, so as to hold the said movable frame b^2 in the position shown in full lines in Fig. 1. To disengage the frame b^2 from these straps, it is only necessary to push the same forwardly a short distance whereupon the eyes will fall from the hooks and release the frame and permit the same to go to the dotted line position referred to.

The storm front may be entirely moved from the top by unbuttoning the straps b^9 from the buttons b^{10} and pushing the frame b rearwardly until the hooks b^7 becomes disengaged from the props b^8 .

When the movable frame is drawn down against the tension of its spring the strain upon the upper removable frame is resisted principally by the portions b^6 of the respective arms which engage with the rear sides of the top props. Some strain, of course, is also brought upon the straps b^9 , but these straps are principally for the purpose of holding the frame b in proper position within the bow and the greater part of the strain, as before stated, is taken up by the said portions, b^6 . It will be seen that when the movable frame is drawn down to a position shown in Fig. 2 and the spring c^5 thus put under tension, the strain of the main part of each spring upon the inclosing part c' of the plate c will be toward the rear, but this strain will be offset by the pressure exerted by the other arm of the spring upon the sleeve portion c^2 of said plate which will be in a forward direction,

so that in effect there will be no tendency to bend the plate c out of shape or away from the frame, b .

Having thus described my invention, I claim:

1. In a front for vehicles, a stationary frame adapted to be fitted to the front bow of the vehicle top, and arms projecting from the respective sides of said frame, each of said arms consisting of a laterally projecting portion having a connection with said frame, a portion extending downwardly from said laterally projecting portion, the lower end of said downwardly projecting portion having an off-set portion fitted about the front bow and an upwardly extending portion from said off-set portion extending back of the top prop. 70 75 80

2. In a front for vehicles, a stationary frame adapted to be fitted to the front bow of the vehicle top, arms projecting from the respective sides of said frame, each of said arms consisting of a laterally projecting portion having a connection with said frame, a portion extending downwardly from said laterally projecting portion, the lower end of said downwardly projecting portion having an off-set portion fitted about the front bow and an upwardly extending portion from said off-set portion extending back of the top prop, and additional devices for removably connecting said stationary members to said bow. 85 90 95

3. In a storm front for vehicles, a stationary frame removably connected to the front bow of the vehicle, the connecting means comprising arms formed square in cross section and extending through a square-shaped loop or loops on said stationary frame, each of said arms being provided with an offset portion extended about the forward edge of the front bow and also an upwardly extending portion adapted to engage with the rear side of the top prop, a movable frame connected with said stationary frame independent of said arms, and a spring for normally holding said movable frame in inoperative position, substantially as specified. 100 105 110 115

4. In a storm front for vehicles, a stationary frame removably connected to the front bow of the vehicle, the connecting means comprising arms formed square in cross section and extending through a square-shaped loop or loops on said stationary frame, each of said arms being provided with an offset portion extended about the forward edge of the front bow and also an upwardly extending portion adapted to engage with the rear side of the top prop, a movable frame connected with said stationary frame, and means for holding said movable frame in folded position under the vehicle top, substantially as specified. 110 115 120 125

5. In a storm front for vehicles, a sta- 13

stationary frame, a movable frame hinged thereto, a plate secured to each side of said stationary frame, said plate being bent to form an offset portion and also a sleeve, a hinge rod supported in the sleeve portions of said plate, and coiled springs located in the offset portions of said plates, one arm of each of said springs having a connection with the movable frame and the other arm

of each of said springs bearing against said hinge, substantially as specified.

In testimony whereof, I have hereunto set my hand this 7th day of April, 1910.

GEORGE W. SCOTT.
